CLAIM

The ornamental design for a waterproof ring, as shown and described.

DESCRIPTION

FIG. 1 is a rear perspective view of a waterproof ring, showing my new design;

FIG. 2 is a rear elevation view thereof;

FIG. 3 is a front elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is an exploded front perspective view thereof;

FIG. 9 is an exploded front perspective view thereof, showing an intermediate layer;

FIG. 10 is a section view take along line 10-10 in FIG. 2; and,

FIG. 11 is a section view take along line 11-11 in FIG. 2. The broken lines shown in the drawings depict portions of the waterproof ring that form no part of the claimed design. The dash-dot-dash broken lines shown in the drawings denote the boundaries of the claim and form no part thereof.

1 Claim, 10 Drawing Sheets
